US00D777553S

(12) **United States Design Patent** (10) **Patent No.:** **US D777,553 S**
(45) **Date of Patent:** **** Jan. 31, 2017**

(54) **BRAKE BIAS ADJUSTER KNOB**

(71) Applicant: **Innovatech LLC**, Chicago, IL (US)

(72) Inventor: **Bruce Nesbitt**, Chicago, IL (US)

(73) Assignee: **Innovatch, LLC**, Chicago, IL (US)

(**) Term: **15 Years**

(21) Appl. No.: **29/563,530**

(22) Filed: **May 5, 2016**

Related U.S. Application Data

(62) Division of application No. 29/534,686, filed on Jul. 30, 2015, now Pat. No. Des. 758,825.

(57) **CLAIM**

The ornamental design for a brake bias adjuster knob, as shown and described.

DESCRIPTION

FIG. 1 is a top perspective view of a brake bias adjuster knob of my new design.

FIG. 2 is a bottom perspective view of the brake bias adjuster knob of FIG. 1.

FIG. 3 is a front view of the brake bias adjuster knob of FIG. 1, the rear view being a mirror image thereof.

FIG. 4 is a left side view of the brake bias adjuster knob of FIG. 1, the right side view being a mirror image thereof.

FIG. 5 is a top view of the brake bias adjuster knob of FIG. 1; and,

FIG. 6 is a bottom view of the brake bias adjuster knob of FIG. 1.

The broken lines shown represent unclaimed subject matter and form no part of the claimed design.

1 Claim, 6 Drawing Sheets
